US00D568458S

(12) **United States Design Patent** (10) Patent No.: **US D568,458 S**
Evans et al. (45) Date of Patent: ** May 6, 2008

(54) **RETAIL BLOWING INSULATION MACHINE**

(75) Inventors: **Michael E. Evans**, Granville, OH (US); **Michael W. Johnson**, Lithopolis, OH (US); **Agustin R. Hernandez**, Blacklick, OH (US); **Brian K. Linstedt**, Ostrander, OH (US); **Hugo E. Eccles**, Columbus, OH (US); **John B. Youger**, Columbus, OH (US); **Gregory J. Merz**, Gahanna, OH (US); **Joseph M. Sexton**, Columbus, OH (US); **Jeffrey D. Accursi**, Columbus, OH (US); **Christopher H. Kujawski**, Columbus, OH (US); **Robert O'Grady**, Columbus, OH (US)

(73) Assignee: **Owens Corning Intellectual Capital, LLCDE** (US)

(**) Term: **14 Years**

(21) Appl. No.: **29/268,051**

(22) Filed: **Oct. 27, 2006**

(57) **CLAIM**

The ornamental design for a retail blowing insulation machine, as shown and described.

DESCRIPTION

FIG. 1 is a front elevational view of a retail blowing insulation machine according to the design.

FIG. 2 is a right side elevational view thereof.

FIG. 3 is a back elevational view thereof.

FIG. 4 is a left side elevational view thereof.

FIG. 5 is a top plan view thereof; and,

FIG. 6 is a bottom plan view thereof.

The broken lines showing of portions of a retail blowing insulation machine are included for the purpose of illustrating environmental structure and forms no part of the claimed design.
